REMOVABLE ROOF AND SCREEN TOP FOR
COTTAGES

Henry H. Wenneborg, Springfield, Ill.

Application July 1, 1938, Serial No. 216,978

1 Claim. (Cl. 108—2)

My invention relates to improvements in housing and especially to small buildings; an object being in my invention to provide for small cottages such as camp cottages, tourist cottages and the like or for small dwellings, certain conveniences which may be utilized as valuable facilities adapted to contribute measurably to the health and comfort of those occupying such buildings.

10 A purpose of my invention is to provide a removable roof and a removable screen adjustably supported beneath the roof of such housing construction so that the interior of such a building may be subjected to the direct sunlight any time it is desired to do so.

15 A further purpose of my invention is to provide a removable roof for health protecting cottages wherever they may be, as well as a removable screen supported in the space commonly occupied by a ceiling over a room covered by such a roof and to provide in connection with such a roof construction, such means as may be needed for running water over such a roof to keep it cool on hot days.

20 25 A particular purpose of my invention is to provide a roller supported roof and top screen for small cottages wherein the construction thereof will permit a quick and convenient removal of the roof from over such cottages where it can be rolled to one side with or without such a screen to admit, when desired, the full strength of a health giving sunlight into the room or rooms of such a cottage and wherein the occupants of the cottage may, in privacy, expose their bodies to a sun bath and where, if desired, the strength of such sunlight may be somewhat reduced by not removing the screen from over the room; while in addition to this convenience, I am providing a water pipe with an automatic 30 35 40 shut-off, adapted to run water over the roof when desired for keeping the same cool.

I attain the objects of my invention by the features of improvement described in this specification, recited in the claim and illustrated in the accompanying drawings, wherein like reference numerals indicate like parts in the several figures.

Referring to the figures:

Fig. 1 is a perspective of my invention with the removable roof in proper place.

Fig. 2 is a side view of my invention.

Fig. 3 is a detail illustrating the roller mounting support for my removable roof and the removable screen.

Fig. 4 is a perspective of my invention show-

ing the roof rolled out of place and showing a ceiling screen still registering over the room in the cottage.

Fig. 5 is a detail illustrating the preferred construction of roller support for my removable roof and removable screen.

Referring to some of the essential operating details of my invention and to the advantages derived from utilizing the same, I shall point out the salient features thereof as I refer to the drawings, wherein a small cottage 1 which may be provided with needed windows 2 and doors 3 and a roof 4 which is preferably supported upon run-ways 5 and 6 by rollers 7, 8, 9 and 10.

This roof 4 normally covers and protects cottage 1 but can be removed at will by rolling the same out on to run-ways 5 and 6 until the cottage room 11, defined by the walls of the cottage, is uncovered.

It is obvious that more than one type of device may be used for controlling the movement of roof 4 when out on to run-ways 5 and 6 but I am illustrating a pull rope 12 adapted to be secured to roof 4 for controlling movements of the same so that rope 12 may be pulled one way 20 or the other when removing or returning the roof.

Since it is the purpose of my invention to be able to roll the roof off of the cottage at will to expose the interior of the cottage to the sunlight 30 then it will be noted that ceiling screen member 13 movably supported by rollers 14, 15, 16 and 17 operatively mounted on run-ways 18 and 19, may be effectively utilized as a means of reducing the intensity of sunlight to which the 35 room is exposed.

However, since the side walls 20 of the cottage are supporting roof 4 as well as screen 13 then run-ways 5, 6, 18 and 19 which respectively carry the roof and screen, will be supported by 40 walls 20 as well as extension arms 21 and 22 respectively, preferably held up by support members 23 and 24.

One of the practical uses of my invention is to make it possible for the occupants of such a 45 cottage when desired to take a sun bath in the privacy of their own home and by this novel construction, it will be seen that if desired, a mild sun bath may be taken by leaving screen 13 in place, while, if it is desired to take a sun 50 bath in the full strength of the sunlight, then screen 13 may be rolled from its ceiling position over the cottage room 11 out under the removed roof, thus admitting the full strength of sunlight down into room 11.

It is also conceivable that one of the very great benefits of my invention for such cottages as may provide living quarters for people will be found in the fact that the interior of the cottage 5 may be subjected to the purifying rays of the sunlight at any time that it is practical to do so, to thus provide a thoroughly healthful sanitary measure for the protection of its occupants.

It is also obvious that where climatic conditions 10 will permit it will be a practical and desirable practice to remove the roof and screen on moonlight nights to rest and sleep in the moonlight.

Wherever it may be desired a platform 25 may 15 be provided for the support of chairs, cots and the like out in the cool shade under roof 4 when the same is rolled out off of cottage 1.

It will be noted in Fig. 1 that a water pipe 26 is provided for delivering water out of the mouth 20 27 thereof down onto the top crest 28 of roof 4 so that the water may run out over all four of the sloping surfaces 29, 30, 31 and 32 thereof.

This pipe 26 has a shut-off valve 33 at the base thereof and also a second shut off valve 34 up 25 under the edge of roof 4 to permit roof 4 to automatically shut off the water which might be running on the top thereof, the instant that roof 4 starts to be moved out off of cottage 1.

It will be noted in Fig. 3 that I am providing 30 a rope 35 and a rope anchor 36 for moving screen 13 when it is rolled out on its supporting runways 18 and 19 off of cottage 1.

It will be found practical, if desired, to utilize 35 a glass ceiling in place of the screen 13 when sunbathing in winter and also if desired, the area covered by floor 25 may be screened in to provide a cool protected place in summer for chairs and cots and the like for occupants of the cottage.

In the study of the merits of my invention, it 40 will be readily observed that it will be of practical use in any one of a number of living conditions. For instance, for camping purposes, my removable roof and removable screen ceiling construction will be found to be a great advantage to 45 the health and happiness of the occupants. For tourist cottages, this invention is very practical

for the advantages that have been enumerated.

As a means of providing special facilities for 5 sun bathing, for sleeping outdoors under protection, a special cottage of small size could be provided in one's back yard provided with all the facilities of this invention.

Having thus described the nature of my invention, what I claim is:

As a new product of manufacture, a cottage, having four upright walls with windows and 10 doors to define a housing, and comprising in combination, a removable roof extending over said walls when in normal position and a removable screen extending over the room defined by said walls and over said roof, a pair of parallel tracks 15 secured to two of said opposite walls adjacent the top edge thereof, and on the outside surface of each respectively, said tracks each shaped to define in U formation one supporting surface therefor, and an integral rail for the support of 20 rollers therefor; a second pair of parallel tracks like the first pair but each track respectively fixed on the inside of the same walls supporting the outside tracks, said inside tracks each having one surface for its support against said wall and 25 an integral rail for the support of rollers, said rollers operating on said outside tracks establishing support connection on the outside tracks for said roof and said rollers on the inside tracks respectively establishing support connection for 30 said screen covering said room within said walls, an extension frame projection from each of said track supporting walls and an extension of said tracks operatively supported on said frame, said extension frame anchored to said walls and provided with upright supports at its outer terminal; and means connected with said roof and said screen for manually rolling them off of said cottage and back on again at will; whereby said roof may be optionally removed horizontally from its 40 normal position covering said cottage walls, and whereby said screen may be likewise removed from its position over said cottage room when it is desired and replaced at will by the manipulation of said control means.

HENRY H. WENNEBORG.
